UNITED STATES PATENT OFFICE.

PETER FLANSBURG, OF MANISTEE, MICHIGAN, ASSIGNOR TO SOLOMON H. GOLDBERG,
OF CHICAGO, ILLINOIS.

EGG CRATE.

Application filed June 19, 1922. Serial No. 569,543.

To all whom it may concern:

Be it known that I, PETER FLANSBURG, a citizen of the United States, residing in the city of Manistee, county of Manistee, and State of Michigan, have invented certain new and useful Improvements in Egg Crates, of which the following is a specification.

This invention relates to improvements in egg crates and refers more particularly to a double crate arrangement having an inner supporting member carried by wire springs positioned both on the top and bottom of the inner crate to absorb jolting and rough usage in transit.

Among the salient objects of the invention are to provide an egg crate consisting of an outer crate and an inner crate, the inner crate supported by removable wire springs whereby the eggs are supported, so that there is at all times free movement of the inner crate upon the resilient spring supports, preventing the eggs from receiving severe shocks which would break the shells; to provide a crate which may be shipped in a knock-down condition and packed in a very small space when knocked down; to provide a crate which is light and constructed of relatively cheap material. A heavy cardboard, pasteboard or box board will serve, as well as wood or fibre board if the inner crate is supported as hereinafter explained.

Fig. 1 is a perspective view of the crate, parts removed so as to show the positioning of the eggs and the top open disclosing the interior construction.

Fig. 2 is a sectional view of the crate.

Fig. 3 is a detailed view of one of the supporting springs or carriers.

Fig. 4 is a perspective detail of the inner crate construction.

Referring to the drawing, the outer crate 1 is of any desired material, which must necessarily be relatively stiff cardboard, fibre board, wood or heavy fibrous paper board or corrugated box board closed by the lids or flaps 2, which when the box is closed to be shipped are held in place by glued strips 3 of fabric or paper. Holes 3 are punched in the ends of the crate to permit ventilation and also to furnish finger holes for lifting the crate. Further ventilation may be supplied about the sides of the crate and in the

top and bottom if the crate is to be used for perishable goods, such as berries, fruits or vegetables.

In the bottom of the outer crate 1 are positioned the spring carriers 4 which consist in a transverse portion extending across the width of the crate, upright or vertical portions 4^a, and horizontally extending legs 4^b which are spread slightly in order to contact the sides of the crate and thus be held in position when sprung into place. Two or more of these spring carriers are positioned in the bottom of the crate according to the weight that is to be carried. The usual practice is to have a spring at each end and one centrally positioned in order that the inner crate 70 will be supported at the ends and in the center.

On top of these spring carriers is positioned the inner crate which consists of a base portion 5 and side retaining wires 5^a. These sides or uprights 5^a have horizontal legs which are turned back so that they may be hooked onto or engage the slots 6 of the base 5 of the inner crate. These vertical side wires are thus easily removable from the base and are disengaged from the base when shipped to the farmer, or transported in a knock-down condition.

Within the side wires is held the egg cell structure 7, each cell containing eggs 8 as shown in Fig. 1. It is understood that the crates may be made of any desired size so that two dozen eggs or more may be shipped in a single crate.

On the top of the inner crate and egg cell structure is placed another base board 9. On top of this base board are placed additional resilient wire carriers identical to the ones placed beneath the inner crate thereby supporting the inner crate on spring supports 95 whether placed upright or in an inverted position. The top flaps or lids 2 are glued or otherwise fastened in place, and the crate is thus sealed and may be carried with either side up without harming the contents of the 100 crate.

Heretofore, it has been the usual practice to label egg crates cautioning express men and freight handlers concerning the condition of the crates, and as is well known, these 105 precautions are oftentimes ignored and as a consequence the number of cracked or broken eggs in transit is unduly excessive.

When supported by the upper and lower spring supports as shown, the crate may be subjected to very rough usage and carried in either upright or inverted position without harming the contents. The construction is particularly adapted to severe jars and shocks without cracking or breaking the eggs.

- 10 In addition to the use explained in connection with shipping eggs, the crates are particularly adapted to the shipment of perishable vegetables, berries and fruits, which are easily bruised by shocks and rough handling in transit.
- 15 I claim as my invention:
1. In a crate for fragile products the combination with an outer box of an inner crate comprising a bottom and removable side portions, upper and lower relatively stiff base members, upper and lower resilient removable

able means positioned above and below the base members for carrying the inner crate.

2. In a crate for fragile and perishable products the combination with a ventilated outer container of an inner frame carrying 25 member comprising upper and lower bases and side retaining elements, resilient means positioned above and below the base members in the outer crate for supporting the inner carrier.

3. In a crate for perishable and fragile products the combination with an outer container of an inner carrying frame comprising upper and lower bases and side retaining members, resilient removable means positioned within the outer container and above and below the inner base members adapted to support the inner carrier in spring relation to the outer container.

PETER FLANSBURG.
